UNITED STATES PATENT OFFICE.

FREDERICK LIONEL RAPSON, OF LIVERPOOL, ENGLAND.

SELF-STARTING DEVICE FOR INTERNAL-COMBUSTION ENGINES.

1,398,796.

Specification of Letters Patent. Patented Nov. 29, 1921.

Application filed October 16, 1918. Serial No. 258,426.

To all whom it may concern:

Be it known that I, FREDERICK LIONEL RAPSON, a subject of His Majesty the King of England, and resident of Liverpool, in 5 the county of Lancaster, Kingdom of England, have invented a certain new and useful Self-Starting Device for Internal-Combustion Engines, of which the following is a specification.

10 This invention relates to automatic mechanical engine starters or to self-starting devices for internal combustion engines.

With aeroplanes or seaplanes it is impossible at present for a pilot to start his machine, except by a second person turning the propeller, which in case of forced landings, after the pilot has rectified the fault to his engine, he must obtain some one to turn the propeller, while in the case of a seaplane

15 this is impossible. It is not practicable to fit aeroplanes with electric dynamo and accumulator engine starters as the weight and upkeep of the accumulators is too great.

20 In performing stunts for instance the acid in the accumulator would empty.

The present invention has for its object to provide a mechanical device, operable preferably from the driver's or aviator's seat, which device is adapted to start an internal 25 combustion engine of, for instance, an aeroplane, seaplane, or a motor car by giving a powerful impulse to the crank shaft after which the engine will automatically take up its cycle of operation, and thus eliminate the 30 above defects.

A further object of this invention is to 35 provide a highly efficient yet cheap mechanical device which will start an internal combustion engine simply by touching a small 40 foot pedal or a hand lever, and further to provide either automatic or hand operated means to return the device to its initial position ready for the next operation. The 45 entire mechanism is limited to a single shaft and is especially distinguished in that exceptional power is transmitted from two sources through anti-friction screw gearing which enables the engine to be turned at a higher speed than is obtainable with any 50 other device used for the same purpose. Moreover, as numerous other mechanical starters hitherto in use usually require a second and sometimes a third shaft to rewind the mechanism, it will be readily understood that with one shaft the device is much 55 more compact, consequently very easily at-

tached to the chassis or fuselage. Once fitted this device, which is proof against back fires, etc., will give no further trouble other than lubricating at rare intervals, thus 60 overcoming the many difficulties connected with the upkeep of accumulators on electric starters and leakage with compressed air and hydraulic starters.

With these and other objects in view the 65 invention consists in providing a device comprising a member adapted to move axially or longitudinally upon, or in relation to, a second member and rotate the same, the arrangement being such that when it is desired to start the engine the members are 70 released from a normally inoperative condition and the first member imparts rotary motion to the second member to start the engine.

The invention further consists in providing manually operated or automatic means to return the mechanism of the device to its initial position for a further operation.

The invention will now be described with 80 reference to the accompanying drawings in which:—

Figure 1 is a perspective view of one form of automatic mechanical engine starter, showing the parts in their normal or inoperative position;

Fig. 2 is a longitudinal sectional elevation thereof with the parts in similar positions to those shown in Fig. 1;

Fig. 3 is a plan thereof;

Fig. 4 is a cross section taken on the line 4—4 of Fig. 2;

Fig. 5 is a cross section taken on the line 5—5 of Fig. 2;

Fig. 6 is a similar view to Fig. 2 showing 95 the parts about to be brought back to their initial position;

According to one form of this invention as shown in Figs. 1 to 6 a shaft or rod 1 is rotatably mounted in suitable anti-friction and thrust ball bearings 2 and 3 at each end carried by brackets 4 from a trough like frame or the like 5 which may be provided with lugs or other suitable means for connecting it to the chassis of a vehicle or to an 100 aeroplane or the like. Upon the shaft or rod 1 is slidably mounted a nut, sleeve or runner block 6. A helical semi-circular groove or the like 7 is cut along a portion of the length of the shaft or rod 1 and a similar co-operating groove 8 is also cut in the interior of the nut or block 6. Within these co-operating 105

helical grooves or recesses 7 and 8 is disposed a number of anti-friction rollers or balls 9. These balls or rollers 9 are adapted to return and circulate through a channel or pipe 10 formed or provided in the said nut or block 6. On one end of the threaded shaft or rod 1 preferably the front end adjacent to the thrust bearing 3 is secured a ratchet wheel 11 provided with ratchet teeth 12. Adjacent to the ratchet wheel 11 is slidably mounted on a squared or other suitably shaped portion 13 of the shaft 1, a pinion, gear wheel or the like 14 which is adapted to engage, when in its operative position, with the flywheel 15 of the engine which is formed or provided with teeth 16 to engage with the said pinion 14. The teeth 16 on the said flywheel 15 and gear or pinion wheel 14 are preferably tapered or pointed at their ends as shown at 17 to facilitate their engagement. The pinion 14 is adapted to be moved into engagement with the teeth 16 on the fly wheel 15 by means of a suitable control mechanism or by an operating lever or pedal 18. This lever 18 which is pivoted to a bracket 19 secured in the trough like frame 5 is forked at its lower end to engage with a pin 20 provided on a sliding bar 21. To the sliding bar 21 is secured a bracket 22 formed with a depending fork 23 which is adapted to engage in an annular groove 24 formed in a collar provided at one end of the said pinion wheel 14. The sliding bar 21 which is normally pressed inwardly by a spring 25, 30 is extended forwardly and formed with a slot 26 which is adapted to engage one end of a lever 27 pivoted at 28 to a bracket 29 preferably formed integrally with the bracket 4. The other end of this lever 27 is connected to a boss 30 of a member 31 which is adapted to slide on the main shaft 1. The 40 slideable member 31 is prevented from rotating by fixed guides 32 secured to the bracket 4 and passing through slots 33, formed in the said member. The slideable member 31 is also provided with one or more 45 spring pressed pawls 34 which are adapted to engage with the ratchet teeth 12 formed on the side of the ratchet wheel 11 to hold the latter wheel 11 and the shaft 1 against 50 rotation. The ratchet wheel 11 and the slideable member 31 are formed with co-operating cone shaped faces 35 and 36 respectively to frictionally engage and gradually stop the motion of the shaft 1 when the operating lever or pedal 18 is released. Suitable spring 55 pressed shoes 37 may be provided on one of the cone shaped faces, if desired, to enable the ratchet wheel 11 and shaft 1 to be frictionally engaged before being positively locked by the pawls 34 engaging in the teeth 12.

The slot 26 in the sliding bar 21 is elongated to enable the said bar 21 to move the pinion 14 into engagement with the flywheel

15 before the shaft 1 is unlocked through the medium of the lever 27 and members 11 and 31. Between the rear end of the runner block 6 and the rear bracket 4 or a ball race 38 thereon, and surrounding the shaft 1 is disposed a strong coiled compression spring 39, preferably square in cross section, which is adapted to force the said block 6 along the threaded shaft 1 when the latter is disengaged by the members 11 and 31. Within this coiled spring 39 and surrounding the shaft 1 is disposed a winding coiled tension spring 40 which is secured at one end 41 to the shaft 1 and at its other end 42 to a sleeve 43 freely mounted on the said shaft 1. This latter spring 40 which is normally wound to a high tension is adapted to rotate the threaded shaft 1 when the previously mentioned pawl carrying member 31 is moved out of engagement with the ratchet wheel 11 and thus provide an initial turning of the shaft 1 at a high speed; which rotation is continued by the pressure of the other or compression spring 39 on the runner block 6. The sleeve 43 is provided with 45 preferably a pair of outwardly sprung pressed plungers 44 which are adapted to co-operate with and engage in suitably arranged slots 45 cut in the end of a cylinder 46 connected to the rear face of the runner block 6 in such a manner that the cylinder 46 engages with the sleeve 43 and rotates the latter to rewind the inner or tension spring 40 when the runner block 6 is revolved on the shaft 1 in the manner to be hereinafter 50 described. The spring pressed plungers 44 are placed on sleeve 43 to facilitate the engagement of the cylinder 46 with this sleeve. If fixed extensions were provided on the sleeve 43, it might happen that the cylinder 46, when rotating, would not engage. By making the ends with the projection movable, should any such slip occur, a positive engagement would be permitted during a further rotation of the cylinder 46. The 55 outer periphery of the runner block 6 is formed with longitudinal grooves or teeth 47 which are adapted to co-operate with longitudinal teeth or grooves 48 formed on a portion of the inner periphery of an outer cylinder 49. Upon a reduced flanged extension 50 of this outer cylinder 49 is slidably mounted a pinion 51 which is adapted to engage with the teeth 16 on the flywheel 15 when moved into engagement by the runner block 6. The outer cylinder 49 is slidably mounted and adapted to rotate freely on the shaft 1 when the runner block 6 is being brought back to its initial position by the engine. A plurality of plungers 52 are 60 secured to the pinion wheel 51 which are normally pressed inwardly by springs 53 to keep the rewinding pinion wheel 51 clear of the flywheel. These plungers 52 are adapted to be engaged by the runner block 6

when pressed forwardly by the compression spring 39 and move the rewinding pinion 51 into engagement with the flywheel 15. When the rewinding pinion wheel 51 engages the flange 54 on the reduced portion of the cylinder 49 the latter will be carried forward a short distance. To the rear end of the outer cylinder 49 is secured a ratchet wheel 55 which is adapted to be engaged by a spring pressed pawl 56 carried by a casing 57 mounted on the frame 5 of the device. The pawl 56 is adapted to engage with the ratchet 55 and hold the cylinder 49 against rotation in the opposite direction during the rewinding of the tension spring 40 and prevent rotation of the cylinder 49 when the parts are returned to their normal or inoperative position. To allow for the sliding movement of the cylinder 49 the teeth on the ratchet wheel 55 are made wider than the pawl 56. The pinion wheel 51 may be formed with tapered engaging teeth, as previously described, to engage with the teeth 16 on the flywheel 15 when moved by the runner block 6 or the alternate teeth 16 of the flywheel may be cut back, as shown, to facilitate the engagement or disengagement. When the starting pinion 14 on the shaft 1 is moved out of engagement with the fly-wheel 15 the rewinding pinion 51 at the other side of the flywheel 15, returns the mechanism to its normal position. This latter pinion wheel 51 is moved out of engagement by the runner block 6 engaging stops 58 which are formed or provided at the rear end of the internal grooves 48 in the outer cylinder 49 and also by the springs 53 on the plungers 52. A suitable cover or casing of aluminium or other material may be provided over the device to keep the same clean and prevent the entry of dirt and dust if so desired.

In order to prevent the device from becoming damaged in the event of the engine backfiring with either the starting or rewinding pinions or both in mesh with the flywheel 15 the pawl 56 is slidably mounted in the casing 57. This pawl 56 which is normally pressed into engagement with the teeth 55 by a spring 59, is pivoted in a carrier 60 which is slidably mounted and movable on a rod 61 against the action of a spring 62. The pawl 56 is provided with extensions or rollers 63 which are adapted to engage with cam shaped surfaces 64 formed on the lower portion of the casing 57. Thus when the cylinder rotates in the opposite direction, under excessive pressure, the pawl 56 will be carried around by the ratchet 55 and be disengaged automatically and thereby cause no damage to the starting mechanism of the device.

It will be understood that when the device is fitted on a motor car or an aeroplane the operating lever 18 may be operated from the

driver's seat or other convenient part of the vehicle or machine through the medium of levers, links or other connecting devices, or the lever may be operated from a foot pedal 65 connected thereto by a swivel connection 66 as shown in the drawings.

In operation and when it is desired to start the engine, the operating or control lever of the device 18 is turned on its fulcrum to slide the bar 21 against the action of the spring 25 and slide the starting pinion or gear wheel 14 on the forward squared end 13 of the shaft 1 into engagement with the flywheel 15. Further movement of the bar 21 will turn the lever 27 on its pivot and withdraw the member 31 and the pawls 34 out of engagement with the ratchet wheel 11 on the shaft 1 and allow the shaft 1 to be rotated at a high speed by the winding tension spring 40 and also by the main compression spring 39 pressing on the runner block 6. Thus the flywheel 15 will be given several revolutions to start the engine through the medium of the pinion wheel 14 on the squared portion 13 of the shaft 1 of the device. When the runner block 6 reaches the end of its travel along the screwed portion of the shaft 1 the springs 53 on the plungers 52 are compressed, the rewinding pinion 51 is moved into engagement with the flywheel 15 and the cylinder 49 is carried forward. When the pedal or operating lever 18 is released the spring 25 returns the sliding bar 21 back to its normal position and the starting pinion 14 is moved out of engagement with the flywheel 15. At the same time the member 31 is brought into engagement with the ratchet wheel 11 by the operation of the lever 27. Thus the shaft 1 is first frictionally engaged by the shoes 37 engaging the ratchet wheel 11 and then positively locked against rotation by the pawls 34 engaging the ratchet teeth 12. It will be understood that the teeth 12 of the ratchet wheel 11 may be shaped to disengage the pawls 34 in the event of any excessive strain on the device due to backfire of the engine.

The rewinding pinion 51 which is now in engagement with the flywheel 15 and which is already set in motion by the cycle of operations of the engine, rotates the outer cylinder 49 to turn the runner block 6 back to its normal position, rewind the coiled spring 40 through the medium of the slotted cylinder 46 and sleeve 43, and compress the main coiled spring 39. The runner block 6 then engages the stops 58 on the interior of the outer or covering cylinder 49 and moves the same rearwardly to withdraw the rewinding pinion wheel 51 out of engagement with the flywheel 15. The rewinding pinion 51 will be withdrawn clear of the flywheel 15 at the latter portion of the movement of the cylinder 49 by the springs 53 on the plungers 52. The device is now ready for further use when desired.

It will be seen that the tension spring 40 is only rewound during the latter portion of the rotation of the runner block 6 in the returning movement thereof.

5. What I claim is:—

1. A mechanical engine starter comprising, a gear connected with the crank shaft of the engine, a main shaft extending parallel with the axis of the gear, a runner block 10 having screw threaded engagement with the shaft, spring means coöperating with the runner block to cause it to rotate the shaft, means to connect the shaft and gear, and means thrown into action by the movement 15 of the runner block and driven by said gear to place the spring means under tension.
2. A mechanical engine starter comprising, a gear connected with the crank shaft of the engine, a main shaft extending parallel with the axis of the gear, a runner block 20 having screw threaded engagement with the shaft, spring means coöperating with the runner block to move it longitudinally of the shaft for rotating the shaft, means to connect the shaft and gear, means 25 to turn the runner block upon the shaft to cause it to travel in an opposite direction thereon to place the spring means under tension, and means operated by the movement 30 of the runner block for moving the turning means into operative position.
3. A mechanical engine starter comprising, a gear connected with the crank shaft of the engine, a main shaft extending parallel with the axis of the gear, a runner block 35 having screw threaded engagement with the shaft, spring means coöperating with the runner block to move it longitudinally of the shaft for rotating the shaft, means to 40 connect the shaft and gear, means to turn the runner block upon the shaft to cause it to travel in an opposite direction thereon to place the spring means under tension, means operated by the movement of the runner block 45 for moving the turning means into operative position, and means adapted to hold the shaft against rotation and to release the same.
4. A mechanical engine starter comprising, a gear connected with the crank shaft of the engine, a main shaft extending parallel with the axis of the gear, a second gear 50 carried by the shaft to rotate therewith and

be shifted longitudinally thereof into and out of engagement with the first named gear, means for holding the shaft against rotation and to release the same so that it is free to turn, common means to shift the second gear longitudinally of the shaft and to actuate the holding means, a runner block having screw threaded engagement with the shaft, spring means coöperating with the runner block to move it longitudinally of the shaft for rotating the shaft, means to turn the runner block upon the shaft to cause it to travel in an opposite direction upon the shaft to place the spring means under tension, and means operated by the movement of the runner block for moving the turning means into operative position.

5. A mechanical engine starter comprising, a gear connected with the crank shaft of the engine, a main shaft extending parallel with the axis of the gear, means to hold the shaft against rotation and to release the same, a cylinder surrounding the shaft, a runner block arranged within the cylinder to move longitudinally thereof and turn therewith and having screw threaded engagement with the shaft, spring means arranged within the cylinder and engaging the runner block to move it longitudinally of the cylinder, pawl and ratchet means to prevent the cylinder from turning in one direction, a second gear connected with the cylinder to turn it, means operated by the movement of the runner block to shift the second gear into and out of engagement with the first named gear, a third gear driven by said shaft, and means to shift the third gear into engagement with the first named gear.

6. A mechanical engine starter comprising, a rotatable shaft, means for connecting the shaft with the engine for starting the engine, a torsional coil spring surrounding the shaft and connected therewith to turn it, a runner block having screw threaded engagement with the shaft, and means to cause the runner block to travel longitudinally of the shaft including a compressible coil spring surrounding the shaft and engaging the block.

In testimony whereof I have hereunto signed my name.

FRED. LIONEL RAPSON.
